UNITED STATES PATENT OFFICE

127,032

DESIGN FOR A DRESS

Adelé Brody, Dorchester, Mass., assignor to Murray White Company, Boston, Mass., a corporation of Massachusetts

Application October 31, 1939, Serial No. 87,950

Term of patent 3½ years

To all whom it may concern:

Be it known that I, Adelé Brody, a citizen of the United States, residing at 119 Glenway Street, Dorchester, Massachusetts, have invented a new, original, and ornamental Design for Dresses, of which the following is a specification, reference being had to the drawing accompanying the same, forming a part thereof:

In the drawing:

In the drawing the panels on each side of the blouse lay over the front of the blouse, being fastened at the shoulder and near the waist to the blouse. The lines in the panels represent pleating.

I claim:

The ornamental design for a dress, as shown and described,

ADELÉ BRODY,
